UNITED STATES PATENT OFFICE.

ISAAC N. WOODWARD, OF WILD ROSE, WISCONSIN.

DESIGN FOR A FULCRUM FOR FORKS.

SPECIFICATION forming part of Design No. 27,275, dated June 29, 1897.

Application filed December 3, 1896. Serial No. 614,366. Term of patent 7 years.

To all whom it may concern:

Be it known that I, ISAAC N. WOODWARD, a citizen of the United States, residing at Wild Rose, in the county of Waushara and State of Wisconsin, have invented and produced a new and original Design for a Fulerum for Forks; and I do hereby declare the following to be a full, clear, and exact description of the same, reference being had to the accompanying drawing, forming a part thereof.

This invention relates to a design for a fulcrum for forks such as are used for agricultural purposes, as digging.

In the accompanying drawing I have illustrated my design by a perspective view.

As shown in the drawing, A designates a plate having upwardly-bent front and rear edges a a' and rounded corners. From the upper side of the plate adjacent to the forward edge projects a bar B, the lower end of which is bent inward and has a laterally-projecting portion b , the rear edge of which is

straight, while the forward edges are slightly curved to a point adjacent to the junction of the bar. This bar is round, and the upper end is flattened and formed into diverging members b' , the terminals of which are semi-circular.

C designates a bar the lower end of which is curved forwardly and slightly flattened, the upper end projecting and having on one side a concave recess c , the side opposite thereto being convex. The bar B is of less length than the rear bar C.

What I claim is—

The design for a fulcrum for forks as herein shown and described.

In testimony whereof I affix my signature in presence of two witnesses.

ISAAC N. WOODWARD.
